UNITED STATES PATENT OFFICE.

JOHN W. SIMONDS, OF GREENVILLE, TEXAS.

TRACE-FASTENER.

No. 845,273.

Specification of Letters Patent.

Patented Feb. 26, 1907.

Application filed February 10, 1906. Serial No. 300,464.

To all whom it may concern:

Be it known that I, JOHN W. SIMONDS, a citizen of the United States, residing at Greenville, in the county of Hunt and State 5 of Texas, have invented a new and useful Trace-Fastener, of which the following is a specification.

This invention relates to trace-fasteners, and has for its object to simplify and improve 10 the construction and increase the utility and efficiency of devices of this character.

With these and other objects in view, which will appear as the nature of the invention is better understood, the invention consists in 15 certain novel features of construction, as hereinafter fully described and claimed.

In the accompanying drawings, forming a part of this specification, and in which corresponding parts are denoted by like designating characters, is illustrated the preferred 20 form of the embodiment of the invention capable of carrying the same into practical operation.

In the drawings, Figure 1 is a plan view, 25 and Fig. 2 is a side elevation, of a portion of a swingletree and trace with the improvement applied.

The improved device comprises a member 10, preferably in annular or ring shape and 30 with a radial loop 11 communicating therewith, the loop being less in thickness than the body of the annular member, as shown in Fig. 1. Movably engaging the member 10 is a link 12, adapted to enter the loop 11, and 35 movably coupled to the link 12, as by a clip 13, is the trace, a portion of which is represented at 14. A portion of a swingletree is represented at 15 with an eye 16, movably supporting a hook 17, the entrance 18 of the 40 hook being less than the thickness of the member 10, but greater than the thickness of the loop portion 11. By this arrangement it will be obvious that when the member 10 is disposed with the thinner loop portion 11

presented to the contracted entrance 18 of 45 the hook 17 it will pass therethrough and enable the larger annular member to pass into the larger interior of the hook, when by returning the link 12 to its position in the loop the trace will be coupled to the swingletree 50 and cannot be released therefrom unless the annular member be again disposed with the thinner loop disposed for passage through the contracted entrance to the hook. It is obvious, therefore, that so long as any strain is imparted to the trace to hold the link 12 in engagement with the loop 11 the trace will not 55 be released. The trace can be released only by disposing the member 10 in a very unusual position, a position it will not assume 60 while the device is in use or strain is applied to the trace.

The device is simple in construction and can be readily applied to any form of trace.

Having thus described the invention, what 65 is claimed is—

1. In a trace-fastener, an annular member having a radial loop communicating therewith and of less thickness than the annular member, a link movably engaging said loop, 70 and a hook having a contracted entrance adapted to pass over the reduced loop but too small to pass over the body of the annular member.

2. The combination with a whiffletree having a hook formed with a contracted entrance, an annular member having a radial loop less in thickness than the annular member and less than the entrance to said hook, 75 a link movably engaging said loop, and a 80 trace movably coupled to said link.

In testimony that I claim the foregoing as my own I have hereto affixed my signature in the presence of two witnesses.

JOHN W. SIMONDS.
